GUNNAR ROOS, OF STOCKHOLM, SWEDEN.

REFRIGERATING MACHINE.

Application filed March 20, 1926, Serial No. 96,198, and in Sweden March 28, 1925.

The present invention belongs to that class of refrigerating machines which are based upon the absorption process. The novelty according to the invention consists in arrangements for causing an effective circulation of the solution as well as a sufficient evaporation and absorption.

An arrangement of the invention is shown diagrammatically in the accompanying drawing.

In the figure there is shown a generator or still 1, from which issues a pipe 3 surrounded by a cooling pipe 4, the still being provided at the bottom thereof with a pipe 9 for the liquid. In the lower part of the generator or still there is arranged a chamber 5. In this chamber the lower end of one or more pipes 6 are arranged, the upper ends of which are curved and open above the uppermost of a plurality of perforated cupshaped shelves 27, which are arranged above the liquid level *a* in the upper part of the generator 1. Similar shelves also are arranged on the walls of the upper part of the chamber 5. From the chamber 5 above the uppermost shelf extends a pipe 8 controlled by a valve 7. The chamber 5 may, if desired, be placed outside the generator 1, without affecting the mode of operation. Furthermore the valve 7 may, if it is found desirable, be placed in such a manner that it is surrounded by or is within the generator 1.

The pipes 3, 8, 9, leading from the generator 1 are connected to a container 2, which serves also as an evaporator and absorber. The pipe 3 opens into the top of the container 2 in such a manner, and the side walls of the container are provided with such arrangements that the liquid entering through the pipe 3 into the upper part of the container 2 is at once spread over the side walls of the container and is caused to run down slowly to the bottom of the said container. Such arrangements may be carried out in many different manners. The arrangement illustrated consists of an open channel 22 at the side walls of the upper part of the container. The pipe 3 opens above the said channel, the bottom of which is perforated close by the walls of the container. Below this channel the side walls of the container are provided with channel shaped shelves 23, which extend spirally down to the vicinity of the bottom of the container. Instead of these channels, shelves, which are displaced one below the other, may be used. Whichever arrangement

is used, there must be an intimate connection of the arrangement to the walls of the container. For this reason it is advisable to shape the walls of the container in such a manner, that the liquid from the pipe 3 is well divided upon the walls and furthermore is delayed, with regard to its downward motion. Such a shape may be obtained by moulding the shelves directly into the side-walls, whereby is also obtained an increase in the area of the wall, which is of great importance for the transmission of heat from the outside of the walls.

The pipe 9 from the still 1 opens into the container 2 above an arrangement consisting of a number of cupshaped shelves or trays 24 arranged one above the other, the bottoms of these shelves or trays 24 being perforated in such a manner that the liquid from the pipe 9 is caused to fall from the one shelf to the next in a rain or spray. The shelves 24 are supported and spaced apart by vertical rods 25. The lowermost shelf 26 is not perforated but has a central opening, to which the outlet pipe 8 is connected.

The vertical position of the container 2 in relation to the generator 1 as well as the arrangement of the pipe 9 are such, that when the liquid in the generator has the level *a*, the said liquid without further assistance may be able to flow by gravity into the container 2 through the pipe 9.

Furthermore the arrangements of the container 2, the pipe 8, the valve 7 and the chamber 5 are chosen in such a manner that the liquid level *b* in the pipe 8 falls at or somewhat above the level *c* in the chamber 5. It may be assumed that the machine works with a solution of ammonia in water and that the cooling jacket 4 and the absorber and evaporator contain some gas or gases, which are not or only slightly soluble in water, for instance air. In the cooling pipe 4 the water flows in the direction indicated by the arrows. The lower part of the generator may be heated by means of steam, electricity, gas-burner or the like.

By heating the generator 1 the expulsion of the ammonia starts in the chamber 5 before in the generator and it also takes place more quickly than in the said generator. Thus an excess pressure in the chamber 5 is produced, and the liquid in the said chamber is caused to flow through the pipes 6 to the upper part of the generator 1, where the liquid is sprayed on the shelves or trays from which it drops

down to the liquid level *a*. When liquid thus is forced out of the chamber 5 the liquid level in this chamber sinks, so that the ends of the pipes 6 are exposed. The gas in the chamber 5 can then pass through the pipes 6 from the chamber 5 to the upper part of the generator, whereby an equalizing of the pressure in the chamber 5 and in the generator 1 takes place. The excess of liquid in the generator flows 10 from the generator through the pipe 9 to the container 2, where it falls on the shelves 24 and is collected on the shelf 26, from which the liquid is drawn away through the pipe 8. As the pressure in the machine at this moment 15 is the same in all parts, the liquid in the pipe 8 flows past the valve 7 into the chamber 5. As the level of the liquid in the chamber 5 is thus raised, the ends of the pipes 6 are closed and a pressure arises in the chamber 5, 20 closing the valve 7 and forcing the liquid through the pipes 6 up to the upper part of the container as already described.

The expelled gas is condensed into a liquid state in the cooling pipe 3 from which it then 25 passes to the channel 22 in the container 2. Because of its flow through the channel 22 and the channels 23, the liquid is brought into a finely divided state and is evaporated. The 30 gas then is mixed with the air in the container. From this mixture the gas is absorbed by the liquid, which is introduced through the pipe 9 and passes downwardly through the trays or shelves 24. By the evaporation of the condensed liquid the walls of the 35 container are cooled as usual in machines of this kind. As the evaporation as well as the absorption takes place in the container 2, this

latter works as a combined evaporator and absorber.

Having now described the nature of my invention and the manner of its operation, what I claim is:

1. In an absorption refrigerating apparatus having the absorber and vaporizer in a common chamber, containing an inert gaseous agent, and in which the cooling agent is introduced in a liquid state, means on the walls of the chamber for distributing the liquid cooling agent in such a manner as to cause the liquid cooling agent to be distributed and vaporized on the walls of the chamber, and distributing means for the absorption liquid supported in spaced relation to the walls of the chamber.

2. In an absorption refrigerating apparatus having the absorber and vaporizer in a common chamber, containing an inert gaseous agent, and in which the cooling agent is introduced in a liquid state, shelves on the walls of the chamber arranged in such a manner as to cause the liquid cooling agent to be distributed and vaporized on the wall of the chamber, and distributing shelves for the absorption liquid supported in spaced relation to the walls of the chamber.

3. The arrangement in absorption refrigerating apparatus recited in claim 2 wherein the distributing shelves for the absorption liquid are arranged centrally within the chamber and spaced therefrom.

In testimony whereof I have signed my name to this specification.

GUNNAR ROOS.
